CLAIM

The ornamental design for a nebulizer, as shown and described.

DESCRIPTION

FIG. 1 is a front, left, and top perspective view of a nebulizer, showing the new design;

FIG. 2 is a rear, right, and bottom perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The broken lines in the drawings illustrate the portions of the nebulizer, which form no part of the claimed design.

1 Claim, 8 Drawing Sheets
